UNITED STATES PATENT OFFICE.

HENRY E. MORTON AND HORACE MANN, OF MUSKEGON, MICHIGAN, ASSIGNEES TO
MORTON MANUFACTURING COMPANY, OF MUSKEGON HEIGHTS, MICHIGAN, A COR-
PORATION OF MICHIGAN.

WORK-HOLDER FOR SHAPERS.

991,347.

Specification of Letters Patent.

Patented May 2, 1911.

Application filed August 17, 1909. Serial No 513,274.

To all whom it may concern:

Be it known that we, HENRY E. MORTON and HORACE MANN, citizens of the United States, residing at Muskegon, in the county 5 of Muskegon and State of Michigan, have invented certain new and useful Improvements in Work-Holders for Shapers, of which the following is a specification.

This invention relates to an improved 10 work holder for shapers or similar metal working machines and it is especially adapted for use in connection with the type of draw-cut shapers shown in United States Patent No. 682,218 to M. and H. E. Morton, 15 for holding large castings which are to be faced upon several sides, at different angles and bored or milled out, such for example as heavy locomotive cylinders.

The object of this invention is to facilitate 20 the centering, alining and adjusting the work to the shaper and to also facilitate the shifting of the work from one position to another to present at different angles the several parts of the casting to be faced or 25 bored.

A further object is to provide a device for the purpose which is so constructed that the work will be held centered during the whole process of shaping or planing, includ- 30 ing the shifting of the work to its several positions, thus insuring accuracy and facilitating the process, and it is also an object of the invention to provide this device with means adapted to facilitate the taking of 35 measurements and the finding of centers, vertical and horizontal lines, etc.

To these ends the invention consists in the construction, arrangement and combination of parts, all as hereinafter more fully de- 40 scribed and particularly pointed out in the claims, reference being had to the accompanying drawings in which—

Figure 1 is a front elevation of a device 45 embodying the invention; Fig. 2, a similar view showing the chuck turned on its axis to hold the work in another position; Fig. 3 is a side elevation of Fig. 1; Fig. 4 is an enlarged longitudinal vertical section through the chuck and work held thereby; 50 Fig. 5 is a side elevation showing the chuck and its bed plate turned upon the floor plate from the position shown in Fig. 2, to position the work for planing the same at right angles to the operation shown in said Fig.

2; Fig. 6 is a plan view of the same with 55 the shaper removed; Fig. 7 is a view similar to that shown in Fig. 1 and showing the bracket for supporting the end of the boring bar, in use; and Fig. 8 is an enlarged sec- 60 tional detail showing the boring bar in use.

This work holder is especially adapted for use in connection with a draw-cut shaper as indicated in outline in the drawings, em- 65 bodying a bed plate A, a column B supporting an adjustable saddle carrying a ram C provided with a tool carrying head D, all constructed, arranged and operated substan- 70 tially as shown in the said Letters Patent before mentioned.

The shaper bed plate A is adjustably se- 75 cured upon a floor plate 1 which is made much greater in area than the shaper bed to accommodate a bed plate 2 thereon at one side of the shaper bed. This floor plate is provided with a series of longitudinally ex- 80 tending parallel T-slots 3 and elongated openings 4 between said slots. The T-slots are to receive bolts for adjustably securing the shaper bed and the bed plate 2 in place thereon, suitable clamps 5 being also held 85 by bolts engaging these slots for assisting in the securing of the bed 2 in such a manner that it may be readily released and shifted upon the upper plane surface of the floor plate to any desired position. When prop- 90 erly located the bed 2 is detachably held against movement longitudinally of the floor plate by wedge blocks 6 between its forward side and pins in the holes 4. Blocks 38 are also provided between plates 39 se- 95 cured to the rear side of said bed and the bed A of the shaper.

The bed plate 2 is provided with trans- 100 verse parallel T-slots 7 and detachably and adjustably secured upon this bed by bolts 95 engaging said slots, are two bearing brackets 8 each formed with a bearing for the hub 9 of a chuck disk 10, which disks are formed in the usual way of making large chucks, with radial slots in which are mounted the ordinary jaws 11 adjusted into or out of engagement with the work by the usual ad- 105 justing screws 12. The hub of each of the chucks is held in the bearing of the brackets 8 by a cap 13 engaging the outer end of the bearing and bolts 14 passing through the caps and engaging screw-threaded openings in the ends of the hub. By turning up the

bolts the chuck is drawn into frictional engagement with the bracket and thus securely held and prevented from turning too readily.

5 The cylinder casting 15 to be faced off is secured to and supported by the chucks 10 by engaging their jaws with the bore of the cylinder, thus supporting said cylinder concentric with said chucks and it is clamped 10 between them by adjusting one bracket toward the other by means of a rack 16 secured to the base plate and a pinion 17 on a shaft mounted on the bracket engaging said rack and turned by a suitable crank 18 applied to the outer end of the shaft. In the hub 9 and cap 13 of each chuck is an axial opening to receive a rod 19 which is put therethrough and through the bore of the cylinder after said casting has been 20 chucked and this rod is screw-threaded at each end and provided with a nut, which nuts may be turned up against the caps 13 and clamp the work securely between the chucks, at the same time clamping each 25 chuck between its bracket and the end of the work and preventing the turning of the chucks.

Each bracket 8 is formed with a flat upper end or table 20 having a plane upper 30 surface parallel with the surface of the bed plate 2 and this table is formed with a longitudinal T-slot 21 and a similar transverse slot 22. By means of a bolt engaging one of the slots, a supplemental table 23 having a rib engaging the outer slot and having a plane upper surface, may be detachably and adjustably secured upon the table 20, and this supplemental table is formed to project inward over the adjacent 35 upper edge of the chuck disk with its inner edge close to the work, so that by the use of a suitable tool, such as a square 24 shown in Fig. 3, accurate measurements may be taken and center lines quickly struck, the 40 upper plane surface of said supplemental table being parallel with the surface of the bed 2 and a fixed distance from the axial line of the chucks, which line is also the axis of the cylinder bore. Measurements may be 45 taken from the table 20, but in order that the square may be supported close to the work to avoid inaccuracies, the supplemental table is provided which may be detached or adjusted as desired. A lateral extension 50 55 is detachably secured to the bracket 8 and forms an extension for the table 20 from which measurements may be taken at a distance to one side of the chuck.

In one of the slots in the table 20 is a bolt 60 for detachably securing a supporting bracket 26 upon said table, said bracket being provided with a rib to engage the other slot and hold the bracket in line. This bracket is provided with a T-slot in its vertical side 65 to receive bolts for adjustably securing a

bearing 27 thereto. Said bearing 27 is provided with a sleeve 28 secured therein to receive the end of a boring bar 29 which is free to rotate and to move longitudinally therein, the opposite end of said bar being 70 attached to and rotated by a shaft 30 in the axis of the ram C.

In machining cylinder castings which are formed with an integral valve chamber such as the casting 31 shown in Fig. 7, the work 75 will be greatly facilitated by being able to bore the chamber while the casting is in the chucks.

As illustrated in Figs. 1 and 2, the casting 80 may be turned to present different faces to the cutting tool, by turning the chucks without removing the casting therefrom, and thus holding the casting centered throughout the entire operation, insuring accuracy 85 and expediting the work.

When castings are being planed which have heavy lateral projections such as the castings shown, detachable and adjustable supports 32 and 33 are provided for such projecting portion, at each side of the brackets 8. The work support 32 is held in place on the floor plate 1 by bolts engaging the T-slots in said plate and at its upper end is provided with a T-slot to receive bolts for attaching an extension member 34 thereto 90 to increase the height of the support if necessary. Arms 35 on the extension member project upward at each side of the work and adjustable centering bolts 36 carried thereby engage the work and hold the same 95 against lateral movement. At the other side of the chuck, to support the laterally extending portion of the casting when the same is turned over with the turning of the chuck, is the work support 33 detachably and 100 adjustably secured to the bed 2 and provided at its upper end with a T-slot by means of which an extension member similar to the member 34 may be attached when desirable. Adjusting or set screws 37 engage screw-threaded openings in the top of the support 105 113 33 upon which the work rests so that said work may be very accurately adjusted.

By mounting the chucks upon a movable bed, the work may be shifted to any desired position without removing it from the chuck, and the chucks combined with the work supports at each side thereof give a very efficient holding means upon which the work may be rotated to present various faces 115 which are thereby located accurately with relation to the axis of rotation.

Having thus fully described our invention what we claim is:

1. The combination of a bed plate, brackets mounted upon said bed plate, a chuck mounted to turn upon each bracket, and means for moving one bracket toward the other to bring said chucks into contact with work placed between. 125 130

2. The combination of a bed plate, brackets adjustably mounted upon said bed plate, a chuck carried by each bracket, and a rod extending through an opening in the axis 5 of each chuck to draw said chucks toward each other and clamp work between.
3. The combination of a bed plate, brackets adjustably mounted upon said bed plate and formed with bearings, chucks having 10 hubs engaging said bearings on said brackets to turn therein, caps engaging the outer ends of the bearings, and bolts passing through said caps into the hubs to draw and hold the hubs in the bearings.
4. The combination of a bed plate, brackets adjustably mounted upon said bed plate and each formed with a bearing, a chuck disk engaging one end of each bearing and each having a hub projecting into the bear- 15 ings, a cap engaging the opposite end of each of the bearings, a rod extending through axial openings in said caps and hubs, and nuts on the ends of said rod engaging the outer sides of the cap.
5. A device of the character described comprising a base plate, means for centering and rotatively holding work mounted upon said base, means for supporting said holding means formed with a plane surface in a 20 certain relation to the base and at a known fixed distance from the axis of rotation of the holding means.
6. The combination of a base plate, brackets on said base plate, chucks rotatively 25 mounted upon said brackets, and a table on one of the brackets the surface of which is at a known fixed vertical distance from the axis of the chuck.
7. A device of the character described com- 30 prising, a bracket formed with a bearing and with a plane horizontal surface at a known fixed distance from the axis of the bearing, a chuck disk having a hub extending into said bearing, and a member detachably se- 35 cured to said surface and forming a table projecting laterally over the upper edge of the chuck disk.
8. A device of the character described comprising a base plate, brackets adjustably se- 40 cured upon said base plate, opposed chucks supported by said brackets to support the work between and permit the turning there- 45 of by the turning of said chucks, and a work support adjustably secured to said base at one side of the said chucks to support a laterally projecting portion of the work.
9. A device of the character described comprising a floor plate for the support of a metal working machine, a bed plate freely movable upon the floor plate at one side of 60 the machine, oppositely facing opposed chucks, brackets adjustably secured upon the bed plate to support said chucks, a work support at one side of the bed plate adjustably secured to the floor plate and means on the 65 upper end of said support for adjustably engaging a laterally extending portion of the work.
10. The combination of a floor plate pro- 70 vided with parallel T-slots and elongated openings and having a plane upper surface upon which a draw-cut shaper is adapted to be secured, a bed plate of lesser area than the floor plate resting thereon at one side of the shaper and adapted to be shifted upon said 75 surface and provided with T-slots in its upper side, means engaging the slots and openings of the floor plate to detachably secure the bed plate in adjusted position thereon, brackets adjustably attached to the bed plate 80 by means engaging the slots and provided with bearings, a rack and pinion for adjusting one of said brackets toward the other, chuck disks having hubs engaging the bearings in the brackets, and adjustable work 85 supports adapted to be detachably attached to the floor and bed plates at each side of the chucks to support laterally projecting portions of the work when turned into engagement therewith by the turning of the 90 chucks.

In testimony whereof we affix our signatures in presence of two witnesses.
